CLOTHESPIN

Lucio Marini, Leominster, Mass.

Application December 29, 1945, Serial No. 638,159

1 Claim. (Cl. 24—84)

1

This invention relates to clothes-pins, particularly of the spring grip type.

Objects of the invention include the provision of clothes-pins of the class described embodying means to secure the same to a clothes-line in clipping and slide relation thereto so that the clothes-pin will remain on the clothes-line at all times, means being provided for detachably securing the pin to the line and further means being provided for securing the clothes to the pin without being folded over the line.

Further objects of the invention include the provision of a spring type clothes-pin having the means to suspend the clothes-pin from the clothes-line in combination with means for suspending the clothes from the clothes-pin, the spring lending a resilient clamping effect both as to the clothes and the line.

Other objects and advantages of the invention will appear hereinafter.

Reference is to be had to the accompanying drawings, in which

Fig. 1 is a view in side elevation showing the new clothes-pin secured to a line in position to clip the clothes;

Fig. 2 is a view similar to Fig. 1 but showing the clothes-pin in position to release the clothes; and

Fig. 3 is a view in front elevation of the new clothes-pin.

This invention comprises a pair of members 10 and 12 secured together in pivoting relationship by means of an intermediately located coil spring 14, the latter having extending ends 16 bent around the elements 10 and 12 as at 18 to normally hold elements 10 and 12 in the position of Fig. 1. Elements 10 and 12 are provided with opposed angular faces 20 for easy insertion of clothes into the region of nip of the clothes-pin and elements 10 and 12 decrease in thickness toward the opposite ends thereof to provide space as at 22 for pivoting the elements apart with reference to the region of nip as shown in Fig. 2. It is preferred that one element should be provided with a projection 24 and the other element with a complementary depression 26 to better secure the clothes.

Element 10 is provided with an opening 28 for the reception of a projection 30 secured to or formed integral with the element 12 and extending therefrom toward element 10 through opening 28. The projection 30 is provided at its free end with a hook 32 and it will be seen that in normal condition, closed condition of the

pin, the opening for the hook is closed, see Fig. 1; but when the elements 10 and 12 are squeezed to open the same, the opening for the hook is released, i. e., moves clear of element 10 so that the clothes-pin may be applied to or detached from the clothes-line 34. However, as the clothes are applied to or detached from the pin, the latter will tend to remain suspended from the clothes-line and will not drop off. It will be clear that the new clothes-pin may be slid along the clothes-line to any position desired but at the same time will not fall from the clothes-line.

The pin comprising this invention may be made from any material desired but it is preferred to mold the same of a moldable plastic material in which case the pin is practically indestructible and cannot be lost by dropping from the clothes-line.

I claim as my invention:

- 20 A clothes pin comprising a pair of one-piece members and a spring providing a pivotal connection of said members in normally closed gripping relation adjacent the lower end of the clothes pin, said members extending free from 25 said pivotal connection in the same general direction in spaced relation to their free ends, one of said members having a projection on its inner face spaced from its free end and provided with a portion having a return bend toward the lower end of the clothes pin defining a downwardly extending hook, the other member having an opening spaced from its free end and receiving said projection with said downwardly extending hook projecting through said opening in position 30 to engage a clothes line to attach the clothes pin thereto, said downwardly extending hook also retaining the clothes pin on said line when said members of the clothes pin are manipulated to 35 open the clothes pin.

LUCIO MARINI.
